DESIGN FOR A SIDE COMB

Albert Girouard, Leominster, Mass., assignor to Fosgood Corporation, Leominster, Mass., a corporation of Massachusetts

Application November 12, 1936, Serial No. 65,864

Term of patent 7 years

To all whom it may concern:

Be it known that I, Albert Girouard, a citizen of the United States, residing at Leominster, in the county of Worcester, State of Massachusetts, have invented a new, original, and ornamental Design for a Side Comb, of which the following is a specification, reference being had to the accompanying drawing, forming part thereof, in which:—

Fig. 2 is a top plan view thereof.

I claim:—

The ornamental design for a side comb, substantially as shown.

ALBERT GIROUARD.
